UNITED STATES PATENT OFFICE.

ORLANDO W. PARSELL, OF BAD AXE, MICHIGAN.

SPRAY-PUMP.

1,265,366.

Specification of Letters Patent. Patented May 7, 1918.

Application filed March 18, 1916. Serial No. 85,055.

To all whom it may concern:

Be it known that I, ORLANDO W. PARSELL, a citizen of the United States of America, residing at Bad Axe, in the county of Huron 5 and State of Michigan, have invented certain new and useful Improvements in Spray-Pumps, of which the following is a specification, reference being had therein to the accompanying drawings.

10 The invention relates to pumps, being more particularly designed for use in the spraying of vegetation, and it is the object of the invention to obtain a durable construction and one which will be maintained free 15 from clogging. To this end the invention comprises various features of construction as hereinafter set forth.

In the drawings:

Figure 1 is a vertical central section partly 20 in elevation; and

Fig. 2 is an elevation of the pump handle, showing the connection of the same with the plunger-operating mechanism.

A is a hollow casing forming the air 25 chamber and delivery conduit of the pump. B is a hollow cylinder or barrel, having a threaded engagement with the lower end of the casing A and extending downward therefrom. C is a barrel of larger diameter telescopically engaging the cylinder B and preferably packed by suitable piston rings D. E is a sleeve member engaging the casing A and adjustably secured thereto by suitable means, such as set-screw F, said member being provided with flanges G for seating upon the barrel or receptacle for the liquid to be pumped. H is the operating handle which is connected with the barrel C so as to telescopically reciprocate the same 35 upon the cylinder B, thereby producing the pumping action, suitable check-valves I and J being arranged respectively at the upper end of the cylinder B and the lower end of the barrel C.

40 It is one of the objects of my invention to provide an operating mechanism for reciprocating the barrel C, which relieves the latter from side thrust, thereby avoiding wear. This I have accomplished by providing as an 45 operating connection a rod K arranged parallel to the axis of the barrels B and C and casing A, and slidably engaging bearings L and L' secured to said casing. The lower end of the rod K has secured thereto a bifurcated member M which extends upon opposite sides of the barrel C and is provided

with bearings M' engaging diametrically opposite trunnions M² on said barrel. Thus the reciprocation of the rod K will communicate a corresponding movement to the barrel 60 C without any tendency toward pulling said barrel against the side of the cylinder B, as would be the case were the axis of the rod K non-parallel to the axis of the cylinder. 65

As the rod K is held by the bearings L and L' from lateral movement it is necessary to provide a fulcrum for the lever or handle H, which is laterally movable to compensate for the angular adjustment thereof. At the 70 same time it is desirable to avoid lateral stress on the rod K which would cause vibration thereof in action. This result I have obtained by providing a fulcrum link N pivotally attached at N' and N² respectively 75 to the lever H and casing A, said link being provided with bearings O and O' upon opposite sides of its center for contacting with coöperating bearings upon the casing A, so as to form stops for limiting the lateral oscillation of the link. As shown in Fig. 1, the lever or handle H is in horizontal position, and in this position the pivot N' is vertically 80 above the pivot N², while the bearing O' to the right of the center of the link is in contact with the bearing at the top of the casing A. This limits the lateral movement of the link N toward the right, but permits limited freedom of movement to the left. In Fig. 85 2 is shown in full and dotted lines the two extreme angular positions of the handle or lever H, in each of which the link N is rocked toward the left so as to bring the bearing O in contact with the coöperating bearing on the top of the casing A. The engagement of 90 these bearings will prevent further movement of the link N to the left, and thus will prevent lateral deflection of the rod K. The link N preferably engages a channel bearing P formed in the top of the casing A, the 95 sides of said channel forming the bearings for the pivot pin N².

As has been stated, the casing A performs the double function of an air chamber and a delivery conduit. To this end there are 105 arranged within the casing a plurality of tubes Q, preferably cast in to a cross partition Q' forming a partition in the casing. These tubes extend downward to near the bottom of the casing and form the delivery 110 pipes for the liquid, while the air which is trapped in the chamber surrounding the

tubes will act as a cushion for maintaining a steady flow. I have found it advantageous to employ a plurality of tubes rather than a single tube, as they may more readily be placed in the core which is used in casting the hollow casing A, while in service they are less likely to become clogged than a single tube.

The check-valves I and J are seated respectively upon bearings formed at the upper end of the cylinder B, which latter forms the plunger of the pump, and the lower end of the barrel C with which said plunger is engaged. For these valves I preferably employ balls, which are self-seating and may be easily removed when necessary for repair.

The liquids which are usually employed for the spraying of trees and other vegetation contain solid matter in suspension, which if permitted to accumulate is likely to clog the pump. It is therefore essential to constantly agitate the liquid within the receptacle and particularly to agitate that portion which is adjacent to the inlet to the pump barrel. For this purpose I have provided an agitator R, which is secured to the lower end of the barrel C and is moved upward and downward therewith in the pumping action. This member is provided with upwardly-inclined portions R' adjacent to the barrel and downwardly-inclined portions R² at the outer ends of the portions R'. The effect of this construction in the reciprocating movement of the barrel is to throw the liquid outward both in the downward and upward movements thereof, so as to carry away from the mouth of the barrel any accumulation of sediment.

To permit of steady pumping it is desirable to provide a relief for a portion of the liquid so as to avoid too high pressure. Such a relief-valve I have arranged at S connected to the lower end of the casing A and controlled by an operating handle S' extending upward and out of the container for the liquid. Instead, however, of discharging the liquid from this valve directly, I have connected to the valve a conduit T, which is extended downward into proximity to the mouth of the barrel C. Thus the small quantity of liquid which is discharged through the relief-valve will assist in agitating the liquid at the mouth of the barrel and preventing the accumulation of sediment.

By reason of the various novel features of construction as above described, my improved pump is highly efficient when used

as a spray pump and in the handling of liquids containing solid matter in suspension.

60

What I claim as my invention is:—

1. In a pump, the combination with a casing and a plunger thereon, of a pump barrel telescopically engaging said plunger, a rod slidably secured to said casing and held in parallelism to the axis of said plunger and barrel, the lower end of said rod being attached to the barrel, a lever for actuating the upper end of said rod pivotally attached thereto, and a fulcrum link for said lever connected to said casing, said link being provided with stop bearings upon opposite sides of said center for limiting the lateral angular deflection thereof during the operation of said lever. 75

2. In a pump, the combination with a reciprocating plunger, of a rod for actuating said plunger, bearings for said rod, compelling rectilinear movement thereof, a lever for actuating said rod pivotally attached thereto, and a fulcrum link for said lever pivotally attached thereto and to a member rigid with said bearings, said link being provided with stops upon opposite sides of the center thereof for engaging said fixed member to limit lateral deflection of the link. 80

3. In a pump, the combination with a casing, of a reciprocating plunger, a rod for actuating said plunger, bearings secured to said casing for engaging said rod and compelling rectilinear movement thereof parallel to the axis of said plunger, a lever pivotally attached to said rod, and a fulcrum link for said lever pivotally attached thereto and to said casing, said link having oppositely-extending wing portions provided with angular faces providing a limited clearance for angular deflection, and operating as stops for limiting said angular movement. 95

4. In a pump, the combination with a casing forming an air chamber and delivery conduit, of a plunger depending therefrom and a barrel telescopically engaging said plunger, means for reciprocating said barrel in relation to said plunger, a relief-valve for said casing, and a conduit extending from said relief-valve to the mouth of said barrel and forming a means for agitating the liquid and preventing the accumulation of sediment thereat. 105

In testimony whereof I affix my signature.

ORLANDO W. PARSELL
